(57) **CLAIM**

The ornamental design for a hip-mounted camera jib, as shown and described.

DESCRIPTION

FIG. 1 is a front, top and left side perspective view showing my new design.

FIG. 2 is a left side view.

FIG. 3 is a right side view.

FIG. 4 is a top view.

FIG. 5 is a bottom view.

FIG. 6 is a front view; and,

FIG. 7 is a rear view.

The broken or dotted lines in the drawings are only for purposes of illustration and form no part of the claimed design. The hip-mounted camera jib is used by a camera operator to support a camera.
